US0D1089115S

(12) **United States Design Patent** (10) **Patent No.:** **US D1,089,115 S**
(45) **Date of Patent:** **** Aug. 19, 2025**

(54) **POWER ADAPTOR**

(71) Applicant: **GUANGDONG BESTEK MEDICAL DEVICES CO., LTD.**, Shenzhen (CN)

(72) Inventor: **Xinhua Xu**, Shenzhen (CN)

(73) Assignee: **GUANGDONG BESTEK MEDICAL DEVICES CO., LTD.**, Shenzhen (CN)

(**) Term: **15 Years**

(21) Appl. No.: **29/923,377**

(22) Filed: **Dec. 29, 2023**

(30) **Foreign Application Priority Data**

Aug. 14, 2023 (CN) 202330517663.0

CLAIM

The ornamental design for a power adaptor as shown and described.

DESCRIPTION

FIG. 1 is a perspective view of a power adaptor showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depict portions of the power adaptor that form no part of the claimed design.

1 Claim, 8 Drawing Sheets
